ABSTRACT: An improved extendible boom of the unrolled thin wall strip, self-forming, hollow tube-type having overlapping tabs both inside and outside at its longitudinally extending seam; the improvement wherein the tabs of each seam edge consist of an alternating series of wide and narrow tabs with tapered side edges, with the wide tabs of one seam edge overlapping narrow tabs and abutting the tapered side edges of wide tabs, of the other seam edge.

EXTENDIBLE BOOM

BACKGROUND OF THE INVENTION

1. Field of the Invention

A self-forming hollow tube-type boom with interleaved seam locking tabs.

2. Description of the Prior Art

An extendible boom having overlapping equal length tabs at its longitudinal seam as disclosed in copending U.S. Pat. application Ser. No. 662,709, of Rushing and Denton, filed Aug. 23, 1967, now abandoned, tends to have backlash between the tabs when the boom is subjected to torsion.

SUMMARY OF THE INVENTION

In accord with the present invention, the employment of wide tabs with tapered side edges which overlap narrower tabs and abut at their tapered side edges corresponding edges of adjacent wide tabs, eliminates clearance between tabs along the seam and prevents backlash during subjection of the boom to a torsional moment, as in employment of the boom for rotary positioning of a sensor or device at its end.

BRIEF DESCRIPTION OF THE DRAWING

In the drawing:

FIGS. 1 and 2 are fragmentary views of the extendible boom showing details of the improved locking tab construction in unengaged and engaged positions, respectively.

DESCRIPTION OF THE PREFERRED EMBODIMENT

Referring to the drawing, the extendible boom 10 of the present invention, as heretofore, is formed of a narrow, elongated strip 11 of thin springlike material, such as heat treated metal a few thousandths of an inch thick, which is rolled onto a reel (not shown) and held in its rolled up state for storage. When released lengthwise from the reel under proper control and guidance it curls together edgewise and forms itself continuously into a hollow tubular shape as a rod or boom.

In accord with the present invention, opposing series of 40 wide and narrow tabs 15 and 16, respectively, are formed alternately in continuation along the longitudinal edges 12 of the strip 11; the narrow tabs 16 of one edge being opposite to

the wide tabs 15 of the other edge. The two side edges 17 of at least each of the wide tabs 15 are tapered or slanted equal degrees in diverging directions progressively inward of such edges, and so aligned at opposite edges of the strip across the seam that such edges 17 of the wide tabs 15 on one seam side abut the tapered side edges 17 of the adjacent wide tabs 15 of the opposite seam side when the seam is formed by causing such wide tabs 15 to overlap the narrower tabs 16, as in FIG. 2, or vice versa. This arrangement prevents longitudinal clearance between the wide tabs 15 due to the slope of the abutting tapered or slanted side edges 17, while the overlap of tabs, narrow and wide, both inside and outside the boom 10 provides resistance to folding collapse of the seam both inwardly as well as outwardly. A taper having a considerable component at right angles to the direction of seam extension in the region of contact assures locking action against longitudinal movement during twisting of the boom, while any longitudinal component of such taper forwardly facilitates the introduction of such tabs on opposite seam sides to one another when the seam springs together during erection of the boom. A taper of 10° from being perpendicular to the longitudinal axis of the boom is suitable, for example, for the tapered side edges 17 in their region of contact.

We claim:

1. An improvement in an extendible boom comprising: an elongated relatively thin springlike strip having a series of tabs formed on each of its opposite longitudinal edges for assuming overlapping positions to form an abutting seam therebetween when the strip is free to curl together edgewise into a cylindrical configuration; the improvement thereof wherein: the series of tabs on each strip edge consists of alternate wide and narrow tabs, the wide tabs of one edge being aligned with the narrow tabs of the other edge for mutually overlapping relationship therebetween to form the seam; and the wide tabs each have inwardly diverging side edges so located that each side edge of the wide tabs of one seam side contacts a point on the tapered edge of the adjacent wide tabs of the other seam side coexistent with the aforesaid mutually overlapping relationship with the narrow tabs.
